MEANS FOR CLOSING A HORIZONTALLY SWINGING DOOR OF A RAILWAY HOPPER CAR.

George B. Dorey, Westmount, Quebec, Canada, assignor to Enterprise Railway Equipment Company, Chicago, Ill., a corporation of Illinois

Application July 21, 1953, Serial No. 369,359

5 Claims. (Cl. 105—286)

This invention relates to improved hopper door closing means including fulcrums for receiving a removable bar for the purpose of closing a horizontally swinging door of a railway hopper car by a downward movement of the operating bar.

The invention contemplates the employment of fulcrum abutments carried by a door and its supporting hopper structure with the fulcrums located in close proximity to the hinge axis of the door and the respective fulcrums located in spaced relation adjacent the hinge axis of the door to accommodate a removable operating bar therebetween.

The objects of the invention, among others, are: To provide abutments which may be readily applied to existing equipment and conveniently located adjacent the ends of the doors adjacent a car side wall; to provide fulcrum means for receiving an operating bar which will retain the bar in a door closing direction only and preclude the use of such fulcrum means as a means for initiating opening movement of the door in the event of frozen lading and thus ensure against the employment of the fulcrums in an unauthorized manner; and the invention further resides in the details of construction concerned with the invention.

In the accompanying drawings the invention is shown as applied to the pendulously mounted door of a hopper car.

Figure 1 is a side elevational view of a portion of a hopper car showing the improvement applied to the door and hopper structure of a so-called W-type of hopper car, said view showing the door in the normally open pendent position and showing a removable bar positioned between the respective fulcrums.

Figure 2 is a frontal elevational view of the structure shown in Figure 1, said view showing approximately one-half the width of the lower portion of a hopper car and showing the removable bar as positioned between the fulcrums and said bar shown in section;

Figure 3 is a vertical side view of the hopper with the door in closed position and the lower portion of the door and hopper broken away to better illustrate the latch parts.

Figure 4 is a detached longitudinal elevational view of an angle-shaped member carried by the hopper and providing one of the fulcrum seats;

Figure 5 is an end elevational view of the angle-shaped member shown in Figure 4;

Figure 6 is a detached longitudinal elevational view of the plate member carried by the door and providing the other fulcrum seat;

Figure 7 is an end elevational view of the plate member shown in Figure 6.

Referring now to the drawings, 10 indicates the center sill of the car, 11 one of the car side walls, 12 a hopper positioned between the center sill and side wall and including a downwardly sloping floor 13 and inner and outer side walls as indicated at 14 and 15, respectively. Extending around the floor and side walls is a frame

2

16 the edge portion of which defines the margins of a discharge opening 17. The frame includes an upper beam portion 18 which underlies an upper floor 19 sloping downwardly in a direction opposite to the lower sloping floor 13.

5 The upper beam member 18 includes a pair of hinge butts 20—20 which are apertured to receive door hinging pintles 21. Pivotedly mounted on the pintles 21 are a pair of door hinges 22—22 to which is riveted or otherwise secured the door 23. The marginal edges of the door 23 are flanged as indicated at 24 to form a pan-shaped door for enclosing the frame 16 when the door 23 is in closed position. The door 23, when in closed position, is swung thereto upwardly, as shown in 10 Figure 3 to lie at an angle from the vertical plane and to meet with the edge portion of the frame 16. The door 23 may be retained in closed position by a suitable mechanism. A type of latching mechanism with which the instant invention may be employed consists 15 of a hook-shaped member 25 having a shouldered portion 26 extending through the door 23 for cooperation with a latching bar 27 pivotally mounted on the door on a pivot 28 and biased by gravity to lie normally in the plane of the shoulder 26 when the door 23 is closed. 20 Leading to the shoulder 26 there is an inclined striker surface 29 which is adapted to engage the latching bar 27 and raise the same from its biased normally latching position as the door is swung to closed position.

The invention herein is concerned particularly with 25 the means employed for swinging the door 23 towards its closed position and resides in the employment of abutments carried by the beam portion 18 of the frame 16 and the door 23, respectively. Each includes an abutment or bar receiving seat as indicated at 31 and 32, respectively. The bar receiving seats 31 and 32 are spaced apart a sufficient distance to accommodate a removable operating bar 33 therebetween. The bar receiving seat 31 is located substantially in alignment with the pivotal axis of the door 23. The cooperating bar receiving seat 32 is disposed on the door 33 and spaced appreciably from the bar receiving seat 31.

40 The bar receiving seat 31, carried by the frame 16, preferably is provided by an angle-shaped member 34 having one wall 35 welded as at 36 or otherwise secured by rivets to the underside of the upper beam portion 18 of the frame 16. The adjacent wall 37 extends substantially normal to the wall 35 and its central portion is preferably coped as at 38 to present an indent 39 the edge of which constitutes the abutment or bar receiving seat 31.

45 The bar receiving seat 32, carried by the door 23, is preferably provided by a plate member 40 welded as at 41 or otherwise secured by rivets to the outer surface of the door 23. The plate member 40 is preferably extended to project upwardly beyond the body of the door 23, as at 42, and the central portion 43 of said projecting portion 42 of the plate member 40 is deformed to present an indent 44 adapted to register with the indent 39 of the member 34. Said indents 39 and 43 together virtually constitute an elongated opening within which the removable bar 33 is held against undue sidewise displacement while permitting it to be positioned at a substantial distance away from a position perpendicular to the hinge axis of the door 23.

50 The operation of the device will be readily understood by reference to Figures 1 and 3 which show the door 23 in open and closed positions, respectively. Assuming the door 23 is in the position shown in Figure 1, the operator, standing outwardly beyond the side wall 11 of the car, inserts the removable bar 33 between the respective bar receiving seats 31 and 32 as indicated and, 55 by a downward pressure on the outer end of the bar 33,

the door 23 is levered towards closed position to assume the position indicated in Figure 3.

The arrangement of the bar receiving seats 31 and 32 is such as to limit employment thereof to movement of the door 23 in a closing direction only. It precludes their use to effect opening movement of the door 23 to release the latter in the event of a frozen load such as is sometimes necessary when the lading adheres to the door plate.

The instant invention provides a simple means for closing a door and at the same time provides a maximum of safety and convenience in operation.

What is claimed as new is:

1. In a railway car having a hopper with a discharge opening and a door hinged to said hopper adjacent an upper side of said opening and swingable under the effect of gravity to an open position, in combination, a bar receiving member secured to said hopper adjacent said upper side of said opening and having a downwardly facing bar receiving surface, a bar receiving member secured to said door adjacent the hinge axis of said door and having an upwardly facing bar receiving surface in alignment with and spaced outwardly from and below said downwardly facing bar receiving surface, and an operating bar at one end engaging said downwardly facing bar receiving surface and in spaced relation engaging said upwardly facing bar receiving surface and

10

extending outwardly from said bar receiving member on said door.

2. The invention as set forth in claim 1 wherein the bar receiving member on the hopper is an angle shaped member having one wall secured to the hopper and another wall extending outwardly of the hopper and carrying the downwardly facing bar receiving surface.

3. The invention as set forth in claim 1 wherein the downwardly facing bar receiving surface lies substantially along the hinge axis of the door.

4. The invention as set forth in claim 1 wherein the bar receiving surfaces are located along the bottoms of coped sections of the bar receiving members.

5. The invention as set forth in claim 1 wherein the bar receiving member on the door is a plate member having an outwardly extending flange carrying the upwardly facing bar receiving surface.
